ATTORNEY

UNITED STATES PATENT OFFICE.

EDWARD J. WILLMAN, SR., OF LOUISVILLE, KENTUCKY.

VALVE.

Application filed February 14, 1921. Serial No. 444,789.

To all whom it may concern:

Be it known that I, EDWARD J. WILLMAN, Sr., citizen of the United States of America, residing at Louisville, in the county of Jefferson and State of Kentucky, have invented new and useful Improvements in Valves, of which the following is a specification.

This invention relates to improvements in valves especially adapted for use in flush 10 tanks and has for an object the provision of a valve which is seated by a movement in the direction of the water entering the valve and opened against the action of the water.

Another object is the provision of a valve 15 of this character whose operation is controlled by the depth of water in the tank, so that although the valve closes in the direction of the incoming water and closes with 20 the water pressure, its operation depends entirely upon the amount of water in the tank.

Another object is the provision of a valve 25 which embodies the above and other objects, in addition to its simple construction and positive method of operation.

Other objects and advantages of the invention will appear as the following description is read in connection with the accompanying drawings.

In the drawings:—

Fig. 1 is a front elevation of the valve showing a fragmentary portion of a flush tank and the manner of securing the valve 35 in position.

Fig. 2 is a vertical longitudinal section taken centrally of the valve and showing the same in closed position.

Fig. 3 is a like view with the valve open.

Fig. 4 is a plan view of the valve.

Referring specifically to the drawings, wherein like characters of reference denote corresponding parts, the reference character 10 indicates the bottom of a flush tank to 45 which the valve is applied. The valve which is indicated at 11 is designed to control the admission of water to the tank and includes a valve casing made up of separate sections 12 and 13. These sections are cylindrical in 50 cross section, one section 12 being exteriorly threaded at one end as shown at 14 for engagement with a threaded collar 15 which is rotatably mounted upon the adjacent end of the section 13. The opposite 55 end of this last named section is reduced and

is provided with a collar 16 spaced from the end. This end is also threaded as indicated at 17 and is designed to be inserted through an opening in the bottom 10 of the tank and to be secured in position by a lock nut 18. 60 The pipe section 19 may be suitably connected to the extremity of the section 13 for connection with a suitable water supply.

The lower end of the upper section 12 is provided upon the extremity thereof with 65 a valve seat 20 and operating against this seat is a valve 21, the latter being removably secured upon the lower end of a valve stem 22, being clamped thereon between a flange 23 and the lock nut 24. The stem 70 22 extends upward through the top of the upper casing section 12 and carries at its upper end a toothed rack 25. The teeth of this rack are engaged by the teeth 26 of a segment 27. This segment is secured upon a 75 shaft 28, by means of a set screw 29 and the said shaft is mounted in bearing openings 30 which are provided in spaced arms 31 extending from the upper end of the upper casing section 12, the said arms being offset 80 from the casing.

In order to guide the valve stem 22 in its movement, the rack 25 has extending longitudinally upon opposite sides thereof flanges 33 which provide grooves for the reception of guides 32 extending upwardly 85 from the upper end of the casing section 12. The end of the shaft 28 is provided with an arm 34 which carries at its free end a float 35. 90

In the operation of the invention, when the water in the tank is being discharged, the water lowering in the tank will cause the lowering of the float 35 to rock the shaft 28 in its bearings. This movement will, 95 through the toothed segment 27 and the rack 25 impart a downward movement to the valve 21 and open said valve against the pressure of the incoming water. The water will then pass from the valve into the tank 100 through an outlet pipe 36. After the water in the tank has reached a predetermined maximum level, the valve 21 will be again seated due to the rising of the float 35 and the movement of the shaft 28 as the water 105 enters the tank. The valve casing is further provided with an after fill tube 37.

The invention is susceptible of various changes in its form, proportions and minor details of construction and the right is here- 110

in reserved to make such changes as properly fall within the scope of the appended claims.

Having described the invention what is claimed is:—

1. A valve comprising a casing, a valve movable therein, a stem fixed to the valve and projecting outwardly through the casing, a rack on the projecting portion of the stem, said rack being provided with opposite longitudinally extending grooves, a pair of guides carried by the casing and disposed in said grooves and means for engaging the rack to actuate the valve.
2. A valve comprising upper and lower casing sections detachably held together and divided by a transversely extending parti-

tion wall integral with the lower end of the upper section, said wall being formed with a central aperture surrounded by a downwardly facing valve seat, a valve engaging said seat and provided with a stem projecting upwardly through the top wall of the upper casing section, a rack carried by the projecting portion of the stem, a pair of offset brackets carried by the upper casing sections, a rotatable shaft journaled in said brackets, a gear segment fixed to the shaft between the brackets for engaging said rack, an arm fixed to one end of the shaft and a float carried by the said arm.

In testimony whereof I affix my signature.

EDWARD J. WILLMAN, SR.
